United States Patent Office.

JOHN C. CREED, OF OMAHA CITY, NEBRASKA.

Letters Patent No. 85,793, dated January 12, 1869.

IMPROVED RAILROAD-CAR-AXLE BOX.

The Schedule referred to in these Letters Patent and making part of the same

---

To all whom it may concern:

Be it known that I, JOHN C. CREED, of Omaha City, in the county of Douglas, and State of Nebraska, have invented a new and useful Improvement in Railroad-Car Oil-Boxes; and I do hereby declare that the following is a full, clear, and exact description thereof, which will enable others skilled in the art to make and use the same, reference being had to the accompanying drawing, forming part of this specification.

This invention relates to improvements in the construction of railroad-car oil-boxes, the object of which is to cheapen the cost of the same.

It consists of an improved form in which the box and its cover are cast, whereby, when the one is hinged to the other by a single pivot, a close-fitting joint is obtained, without the expense of other finishing.

Figure 1 represents a side elevation of my improved box, and

Figure 2 represents a sectional elevation of the same, taken on the line xx of fig. 1.

Similar letters of reference indicate like parts.

A represents the shell of the box, which is provided with the projection B, and with the bead or rib C around the lower portion thereof, which is so formed in its connection with the shell of the box, in the casting thereof, as to provide the curved recesses or groove D for the reception of the curved end of the cover.

E represents the cover, which is provided with a projection F, corresponding with the projection B on the box, and through which it is hinged to the box by a bolt or pin, G.

The sides of the said cover are provided with beads, corresponding to the bead C on the box, and form the continuation of the latter when in the closed position.

The radius of the curve of the bottom of the box and the groove D is less than that of the centre, on which the cover swings, and the opening of the groove into space at the one side, as at H, is sufficiently low to allow the cover to swing in that direction, to open the box, while on the other side it is of sufficient height to arrest the movement of the cover in that direction, when in a closed condition.

The lower part of the cover, below the beads, shuts into the groove D, as will be clearly understood, and the form or angle of the ends of the several sections of the bead may be that best calculated to insure close fitting joints.

It is not essential, however, that the door be provided with a bead.

The walls of the groove may be inclined, so as to wedge the cover down tightly when closed.

Having thus described my invention,

I claim as new, and desire to secure by Letters Patent—

The box A and cover E, constructed, arranged, and combined together, substantially as and for the purpose described.

JOHN C. CREED.
